SPRING GROUP

John E. Flesch, Los Angeles, Calif., assignor to
American Steel Foundries, Chicago, Ill., a corporation of New Jersey

Application April 21, 1950, Serial No. 157,389

15 Claims.

(Cl. 267—9)

1

This invention relates to a package spring group of the type commonly utilized to support a bolster from the side frame of a railway car truck.

A general object of the invention is to devise a package group of the above-described type wherein a novel economical efficient arrangement is provided to lock the package in assembled relationship.

A further object of the invention is to provide a locking arrangement which will interlock the parts of the spring package in operating assembly to limit expansion of the package and which will readily fit into such package without impairing its function.

A more specific object of the invention is to provide in a spring package comprising top and bottom plates with telescoping followers attached to respective plates, retaining means adapted to fit within the followers and to limit separatory movement of the followers to thereby limit expansion of the package.

A further object of the invention is to provide retaining means which may be easily applied and dismantled from the package.

A different object of the invention is to provide retaining means which will remain with the package during its use and wherein the retaining means are held against vibration to prolong the life of the parts.

A still further object of the invention is to provide retaining means which are compact, convenient and lightweight and have long life in service.

The foregoing and other objects and advantages of the invention will become apparent from a consideration of the following specification and the accompanying drawings, wherein:

Figure 1 is a top plan view of a package spring group embodying the invention with the top and bottom followers fragmentarily shown to clarify the illustration;

Figure 2 is an end elevational view of the group partly in section taken substantially on the line 2—2 of Figure 1, the springs in the left half foreground being removed; and

Figure 3 is a sectional view taken substantially on the line 3—3 of Figure 2.

In the various figures certain details may be omitted where more clearly shown in the other figures.

Describing the invention in detail the novel package spring group comprises top and bottom spring plates 2 and 4 and four load-carrying spring units therebetween, each unit consisting of an outer coil spring 6 and an inner coil spring 8 compressed between the plates. The spring units 6, 8 are disposed at the four corners of the package spring group. The top and bottom plates

2

have peripheral flanges 10 and 12 confining the springs between the plates.

A friction device, generally indicated 14, is positioned centrally of the spring group and comprises a top follower 16 telescoping into a bottom follower 18. The bottom follower is in the form of a rectangular friction casing or housing and comprises spaced generally vertical side walls 20, 20 extending longitudinally transversely of the package, said side walls being interconnected at the ends by generally vertical end walls 22, 22, said side and end walls being formed integral at their lower edges with the bottom plate.

The top follower comprises generally vertical side walls 24, 24 positioned adjacent respective side walls 20, 20 and interconnected by spaced transverse walls 26, 26, said side walls 24, 24 and walls 26, 26 being formed integral at their upper edges with the top plate 2. To facilitate integral casting of the top plate and top follower the holes 27 are formed in the spaced transverse walls 26, 26. The side walls are formed at their lateral edges with wedge faces 28 (Figure 2) in slidable engagement with friction shoes 30, 30, the shoes having frictional engagement as at 32 with wear plates 34 mounted on the respective end walls 22, 22 of the bottom follower.

Each shoe is a hollow structure and is actuated by a spring 36 received therein and compressed as at 38 and 40 between the shoe and the top plate 2. A further description of the friction arrangement is unnecessary inasmuch as the same is adequately shown and described in United States Patent 2,483,181, issued to Claus J. Werner Clasen, on September 27, 1949, for Spring Group.

The present invention contemplates the provision of novel locking means for such a package spring group, said locking means comprising a pair of locking members or keys generally indicated 38, 38, said locking members being received within the top follower 16 in an opening or cavity 40 therein, the cavity 40 being defined between the walls 24 and 26 of the top follower. The cavity 40 is closed at its lower end by a bottom wall 42 formed integral with the lower edges of the walls 24 and 26.

The locking members 38, 38 are oppositely arranged side by side at their upper ends and at their lower ends are offset toward each other and disposed in alignment transversely of the walls 24, 24 of the top follower. Each locking member 38 comprises a flat piece of metal including a shank 44 intermediate its ends, said shank being curved at its lower end and abutting as at 46 against an upwardly tapered surface 48 at the upper end of an upstanding fulcrum or abutment member 50 formed integral with the top side of the bottom wall 42 of the top follower and at its lateral edges formed integral with the walls 26, 26 and extend-

ing generally parallel to walls 24, 24. It will be noted from a consideration of Figure 3 that the upper end of member or web 50 extends between the lower ends of the shanks 44 of the pair of locking members 38, 38 and has its surfaces 48, 48 tapering upwardly. The shank 44 of each locking member merges into a generally horizontal toe 52, the toe extending through transversely or horizontally alignable vertically elongated slots 54 and 56 in adjacent walls 24 and 20 of the top and bottom followers. It will be seen that in locking position each toe engages on its top side as at 58 the related wall 20 at the upper end of the slot 56 therein.

The shank 44 of each locking member extends diagonally upwardly transversely of walls 24, 24 of the top follower through an opening 60 defined between generally horizontal ledges 62, 62 formed on the interior sides of walls 24, 24 at the upper end of the central opening 40 of the top follower. The ledges 62 are formed at their ends integral with walls 26, 26. The opening 60 communicates at its lower end with opening 40 and at its upper end opens into a cavity 64 which is formed centrally through the top plate 2. It will be seen that each locking member 44 abuts at its lateral edge from which its toe extends as at 66 a generally vertical edge of the adjacent ledge 62. The upper end of each locking member 44 is provided with a generally horizontal lug 68 affording a support on its bottom side as at 70 for the associated locking member by seating on the top side of the other ledge 62.

It will be noted that in locking position as shown in Figure 3 the downward force exerted against the toe 52 of each locking member causes the related shank 44 to engage face 48 as at 46 on the side remote from the related toe 52 and to engage the adjacent ledge 62 as at 66 at its opposite side and to engage the lug 68 as at 70 with the other ledge 62. Preferably the top ends of the locking members are ground flat flush with the top side of the top plate 2, whereby when the top plate 2 is seated against its associated truck member such as a bolster, the keys 38, 38 will be maintained in tight engagement with the top follower and thus maintained in position and prevented from rattling.

To disassemble the package spring group, as shown, the package is compressed with the top plate down. The keys will drop out and the package may be expanded and the remaining parts will readily disassemble. To assemble, the parts of the package are assembled as described in the Clasen patent. The package is compressed. Each key 38 is inserted into the top follower through cavity 64, opening 60 and opening 40 and entered with the lower end of the shank abutting against the fulcrum 50 to guide it in a path moving the toe 52 through its related slots 54 and 56. The package spring group may then be expanded whereupon it will be locked as shown.

It will be noted that the bending moment on the keys is confined to the toes 52, 52 and that an ingenious arrangement is afforded to counter-balance the forces against web 50 by the opposing action of the keys, thereby providing a practical structure which fits into the limited space and which will have long life in service.

To reduce initial vertical height, a block of non-ferrous material (not shown) may be inserted at 58.

I claim:

1. A package spring group comprising top and bottom plates, top and bottom telescoping fol-

lowers formed integral with respective plates, said top and bottom followers comprising spaced side walls arranged in parallel adjacent relationship with horizontally alignable vertically elongated slots therein, springs between said plates urging them apart, and means for limiting separatory movement of said plates, said means comprising a bottom wall on said top follower integral with said side walls, an abutment on the top side of said bottom wall between said side walls of the top follower, ledges adjacent the top end of said top follower, keys extending through said top plate between said ledges, each key being seated on one side against said abutment and extending through the slots in the adjacent side walls of the top and bottom followers for abutment at its opposite side with the associated wall of the bottom follower at the upper end of the slot therein, each key having a face formed as a continuation of the last-mentioned side of the key in abutment with a generally vertical face of one of said ledges, each key having a lug extending over the other ledge and seated thereon, said lugs being disposed wholly within a recess in said top plate.

2. A spring group comprising top and bottom plates, springs compressed therebetween, top and bottom telescoping followers connected to respective plates, friction shoes at opposite sides of said top follower in wedge engagement therewith and in frictional engagement with the bottom follower, spring means compressed between the shoes and top plate, and means for interlocking said followers comprising a fulcrum on said top follower between said shoes, a pair of keys supported at their upper ends from portions of said top follower, one of said keys seating against one side of the fulcrum and the other key seating against the opposite side thereof, and each key comprising a toe extending through a vertically elongated slot in a wall of said bottom follower thereadjacent.

3. A spring group comprising top and bottom plates, at least one spring therebetween, top and bottom telescoping followers connected to respective plates, friction means at opposite sides of the top follower comprising shoes in wedge engagement therewith and in frictional engagement with the bottom follower, said top follower comprising a fulcrum at its lower end between the shoes, and means for limiting separatory movement of said followers comprising a pair of keys between the shoes arranged side by side at their upper ends and diverging downwardly and extending at opposite sides of said fulcrum and seated thereagainst, each key having a generally horizontally extending portion projecting through a vertically elongated slot in a wall of said bottom follower, and means on the upper ends of said keys and top follower supporting said keys.

4. A spring group comprising top and bottom plates and springs compressed therebetween, top and bottom telescoping followers connected to respective plates, a pair of keys within said top follower, an abutment member in said top follower extending between said keys and in engagement therewith, each key projecting into a vertically elongated slot in a wall of said bottom follower, each key having a lug at its upper end recessed within said top plate and seated on a portion of said top follower, each key engaging an opposed portion of said top follower along a substantially vertical face.

5. A spring group comprising top and bottom plates and springs therebetween, top and bottom

telescoping followers connected to respective plates, friction means disposed without said top follower in wedge engagement therewith and in frictional engagement with the bottom follower, and means for limiting separatory movement of said plates and followers comprising a pair of keys between the shoes supported for movement with the top plate and top follower and arranged side by side at their upper ends and substantially in alignment at their lower ends, said keys having oppositely extending portions at their lower ends extending into vertically elongated slots in said bottom follower, and abutment means on said top follower extending between the lower ends of said keys and seating the same, said keys extending transversely of the shoes.

6. In a springing device, top and bottom telescoping followers, resilient means urging said follower apart, and means for limiting separatory movement of said followers comprising a key within the top follower and having a shank with oppositely extending lug and toe at its upper and lower ends, a ledge on said top follower beneath said lug supporting the same, said shank and top follower abutting each other along generally vertical faces at a side of said shank opposite said lug, an abutment in said top follower seating said shank on a side thereof from which said lug projects, said toe extending generally horizontally through a vertically elongated slot in a wall of said bottom follower and abuttable at its top side with a downwardly facing surface of said wall at the upper end of said slot to limit separatory movement of said followers.

7. In a springing device, telescoping inner and outer followers, resilient means acting between the followers urging them apart and means for limiting separation of said followers comprising a pair of keys within the inner follower, each key having a portion at one side seated on a surface on said inner follower facing toward the outer end thereof, each key having a portion at the opposite side thereof extending into a slot in the outer follower, said key bearing at one point on said one side against said inner follower and bearing at another point at said opposite side against said follower, said second-mentioned point being located closer to said outer end of said inner follower than said first-mentioned point, the outer ends of said followers affording seats for associated supporting and supported members, said keys having surfaces coplanar with the seat on the inner follower.

8. In a springing device, telescoping inner and outer followers, spring means operatively associated with the followers urging them apart, and means for interlocking said followers, said means comprising a pair of substantially J-shaped lock members extending longitudinally into said inner follower, one end of each member being supported by said inner follower and the other end of each member extending into an opening in said outer follower elongated lengthwise of said followers, abutment means on said inner follower seated against said member at a convexly curved portion thereof, and a surface on said inner follower seating said member at a side opposite that at which said portion seats and disposed closer to the outer end of said inner follower.

9. A spring group comprising spaced spring plates, spring means urging said plates apart and a substantially J-shaped key carried by one of the plates, the head of said J being buttressed

at spaced points at opposite sides thereof against said one plate and the toe of said J being engaged with the other plate to limit movement of said plates apart from each other.

10. A spring group comprising top and bottom spring plates, spring means urging said plates apart, a cavity in the top surface of said top plate, a key having a lug received in said cavity in engagement with an upwardly facing surface of said top plate at one side of said key, said key being engaged at the opposite side thereof with said top plate at a point below the level of said surface, and means on the key engaged with the bottom plate for limiting movement of said plates apart from each other.

11. In a spring group, top and bottom members, resilient means compressed therebetween, and means for interlocking said members in assembled relationship with each other and said spring means comprising a pair of locking elements, each comprising a leg bearing at one side intermediate its ends against one surface of said top member and at its opposite side adjacent one end against an opposed surface of said top member, each element comprising another leg extending from the other end of the one leg into a slot of the bottom member elongated in the direction of compression of said resilient means.

12. A spring group comprising spaced spring plates, spring means urging said plates apart, a key having one end thereof anchored to one of the plates, and a toe on the other end of the key extending angularly therefrom and engaged with the other plate to limit movement of said plates apart from each other under the action of said springs.

13. A spring group comprising spaced plates, spring means compressed between said plates, a cavity in the surface of one plate, a key having a lug in said cavity seated against said one plate, and means on said one plate engaging said key and operative to fulcrum said key into position to engage said other plate, thereby limiting separatory movement between said plates.

14. A spring group comprising top and bottom plates, springs compressed therebetween, and a key having upper and lower ends, one of said ends being removably interlocked with one of the plates and the other of said ends being engaged with the other plate for limiting movement of said plates apart from each other, and means engaging said key operative to fulcrum said one end into position to be removably interlocked with said one plate.

15. A spring group comprising spaced spring plates, spring means urging said plates apart from each other, a pair of keys removably interlocked with one of the plates, toes on said keys engageable with the other plate for limiting movement of said plates apart from each other, and means on said one plate for spreading said keys to engage said toes with said other plate.

JOHN E. FLESCH.
